UNITED STATES PATENT OFFICE.

GEORGE CLAYTON REID, OF CRANFORD, NEW JERSEY, ASSIGNOR TO AMERICAN CAN COMPANY, OF NEW YORK, N. Y., A CORPORATION OF NEW JERSEY.

SHOE-POLISH BOX.

Application filed November 9, 1921. Serial No. 513,918.

This invention relates in general to containers, and is particularly embodied, by way of illustration and as a preferred form, in shoe polish boxes of usual general configuration.

A principal object of the invention is the provision of effective opening means incorporated in the structure of the box itself and operable simply by pressure of the hand.

10 A further object of the invention is the provision of a container of the type above specified which may be constructed with but slight variation from the usual form and without the use of extra material or parts.

15 Another object of the invention is the provision of a self opening container of even superficial form and so arranged that the special opening construction in no way interferes with handling or storing of the package, and is not likely to cause accidental removal of the cover.

20 Numerous other objects and advantages of the invention will be apparent as it is better understood from the following description, which, taken in connection with the accompanying drawings, discloses a preferred embodiment thereof.

25 Referring to the drawings, Figure 1 is an elevational view of a container constructed in accordance with my invention, a part thereof being broken away for convenience in illustration; and

30 Fig. 2 is a plan view thereof. The container, as illustrated in the drawings, comprises a body 11 and a cover 12. The body has a cylindrical wall 13 provided medially with a circumferential rib or bead 14 adapted to serve as a stop shoulder for the depending flange 15 of the cover 12. Said flange 15, when the container is closed, frictionally engages an upper wall part 16 and by reason of the close fit between these parts a practically hermetic closure is provided. The upper wall part 16 is slightly tapered 35 upward as shown. The cover is domed as indicated at 17 for the sake of appearance and capacity and to provide a construction wherein the flange 15 may be sprung in a manner to be hereinafter described to open

the box, the sheet metal of which such containers are usually made being suited to this result.

40 The cover flange 15 is provided with opposed offset portions or protuberances 18 in its edge which, as has heretofore been stated, 55 is above the rib 14 which limits the extent of over-lapping engagement with the body wall. Pressure by the fingers upon the offset portions 18 results in releasing the frictional engagement of the cover flange upon the 60 wall part 16 and permits complete removal of the cover. It will thus be seen that no extra parts are required for opening the box, and the material and operations in constructions vary but slightly from those employed in a plain flange container. The 65 structure is simple and extremely effective in operation, being therefore of very distinct commercial and practical advantage.

70 It is thought that the invention and many of its attendant advantages will be understood from the foregoing description, and it will be apparent that various changes may be made in the form, construction and arrangement of the parts without departing 75 from the spirit and scope of the invention or sacrificing all of its material advantages, the form hereinbefore described being merely a preferred embodiment thereof.

78 I claim:
80 A container, comprising a cylindrical body having a circumferential rib protruding therefrom, and a resilient cover formed with an upwardly curved and domed top and having a flange adapted to frictionally engage 85 the part of the body above said rib only, and provided with offset hollow portions at the bottom edge of the cover adapted to be pressed inwardly by the fingers to spring 90 said cover flange from frictional engagement with said body part, the part of the body above said rib being tapered inwardly towards its top edge and the cover flange being expansible, by reason of said offset 95 portions after it is pressed, relative to said tapered part.

GEORGE CLAYTON REID.
